CLAIM

The ornamental design for a fashion strap, as shown and described.

DESCRIPTION

FIG. 1 is a perspective view of a fashion strap showing my new design.

FIG. 2 is a front elevation view thereof.

FIG. 3 is a rear elevation view thereof.

FIG. 4 is an enlarged left side elevation view thereof.

FIG. 5 is an enlarged right side elevation view thereof.

FIG. 6 is a top plan view thereof; and,

FIG. 7 is a bottom plan view thereof.

The broken lines shown in FIGS. 3 through 7 illustrate portions of the Fashion Strap that form no part of the claimed design.

The ornamental design embodying the invention consists of a longitudinal strip of fabric having a zipper arranged between panels intermediate the ends of said strip, a strap adjuster slide at one end of said strip, a fabric extension adapted to receive a hook and loop fastener at the other end of said strip, and a hook and loop fastener extending from the free end of said fabric extension. A decorative surface may be arranged on a face of said longitudinal strip.
